DRINKING MUG

Victor J. Bergeron, Hillsborough, Calif.
(20 Cosmo Place, San Francisco, Calif.)

Filed Aug. 16, 1962, Ser. No. 71,320

Term of patent 14 years

(Cl. D44—9)

FIG. 1.

FIG. 2.

FIG. 3.

FIG. 4.

FIG. 1 is an elevational view of a drinking mug showing my new design;

FIG. 2 is an elevational view thereof, with the mug rotated 90 degrees from the position of FIG. 1;

FIG. 3 is an elevational view thereof, with the mug rotated 90 degrees from the position of FIG. 2; and

FIG. 4 is an elevational view thereof, with the mug rotated 90 degrees from the position of FIG. 3.

I claim:

The ornamental design for a drinking mug, substantially as shown.
